UNITED STATES PATENT OFFICE.

ERNEST J. BRASSEUR, OF CHICAGO, ILLINOIS, ASSIGNOR TO A. B. DICK COMPANY,
OF CHICAGO, ILLINOIS, A CORPORATION OF ILLINOIS.

SHEET-FEEDING DEVICE.

1,371,068.

Specification of Letters Patent.

Patented Mar. 8, 1921.

Application filed June 12, 1920. Serial No. 388,485.

To all whom it may concern:

Be it known that I, ERNEST J. BRASSEUR, a citizen of the United States, residing in the city of Chicago, county of Cook, and State of Illinois, have invented certain new and useful Improvements in Sheet-Feeding Devices, of which the following is a specification.

My invention relates to sheet feeding devices which are particularly applicable for use with duplicating machines of the type employing a rotary drum, such as are described for example in Patents No. 1054399 and 1054637, to A. B. Dick, dated February 25, 1913. My invention relates particularly to improvements in sheet feeding mechanisms, whereby paper sheets of varying thickness and character may be fed with great accuracy from the top of a pile of sheets to a stencil-duplicating or other machine.

In duplicating machines of the character mentioned various adjustments have been necessary in order to efficiently feed sheets of different character. The length of time, in relation to the rotation of the cylinder, during which the feed rollers engage a sheet in picking the same up from the stack needs to be adjusted when sheets of a lighter or a heavier character are to be operated upon. To pick up one sheet at a time a longer period is required for heavy or thick sheets than for light or thin sheets, and a longer time is required if a sheet has a smooth surface than otherwise.

The amount of pressure exerted upon the stack of sheets by the feed table below the same and the feed rollers above the same also requires adjustment in the case of sheets of different character. The pressure should be greater in the case of thick sheets than in the case of thin sheets. Likewise the point of application of pressure upon the top sheet of the stack by the paper weight rod, which is caused to engage the top sheet when the latter is to be picked up by the feed rollers, should be different for different characters of paper. For thick paper, generally speaking, this rod should engage the paper along a line which is farther away from the feed rollers than it should be in the case of light paper.

I have provided a construction in which a single manual control automatically makes

the three adjustments referred to, namely, 55 the timing of the contact between the feed rollers and the top sheet, the pressure exerted on the paper, and the distance between the transverse rod referred to and the feed rollers. Mechanism is provided whereby 60 the turning of a hand crank or the like moves a pointer over a graduated scale, and at the same time causes such adjustment of the working parts that the three factors referred to will be taken care of during the 65 operation of the machine. I have found that the three factors mentioned bear such a relation to each other that a proportional adjustment of all three will give satisfactory results. My object accordingly is to 70 provide an effective structure for producing the effect desired.

In order that a clearer understanding of my invention may be had, attention is hereby directed to the accompanying drawings 75 forming part of this application and illustrating one embodiment of my invention. In the drawings, Figure 1 represents a side elevation of a rotary duplicating machine embodying my invention; Fig. 2 is a top 80 plan view of the same; Fig. 3 is an enlarged partial side elevation viewed from the same side as Fig. 1, but with various parts broken away to show parts behind the same; Fig. 4 is a vertical section taken on 85 line 4-4 of Fig. 2; Fig. 5 is a horizontal section taken on line 5-5 of Fig. 3; and Fig. 6 is a vertical section taken on line 6-6 of Fig. 3.

Referring to the drawings, the machine 90 embodies the usual rotary drum 1 which may be rotated by the hand crank 2, or by belt connection from a suitable motor to the pulley 3 on the drum shaft 4. A stack of sheets to be fed into the machine is placed 95 on the table 5, and on the apron 5', between the gages 7 and 8, 8, with the forward edges of the sheets beneath the regulator plate 9. During the rotation of the drum the feed rollers 10 on shaft 11 pick up the forward 100 edge of the top sheet, the paper buckling between the feed rollers and the breaker or paper weight rod 12, and the sheet feeding into the machine between the feed rollers and the friction roller 13 above the same in 105 well known manner.

In the form of my invention illustrated a vertical plate 14 is secured at the right

hand side of the machine. This plate has a flanged extension 15 secured to its upper portion, the upper curved surface of this extension being graduated and provided with 5 suitable indicating characters, as is shown at 16. This scale may bear the words "Thin" at one end and "Thick" at the other with the figures 1 to 7, or any other suitable number, between the same. A pointer 10 17 is adapted to be moved over scale 16 into a suitable position for indicating adjustment of the machine for feeding, for example, one sheet at a time of a specified thickness and character.

15 The various adjustments are all made by a hand crank 18 secured to a stud 19 mounted in the plate 14. Stud 19 carries a bevel gear 20 on the inner side of plate 14, this gear meshing with bevel 21 mounted on 20 shaft 22, which is rotatably mounted in brackets 23, 24, on the inner face of plate 14. Shaft 22 is provided with an external screw thread and carries a nut 25 which preferably is of a yoke shape with two internally threaded separated portions mounted on screw 22 as shown.

As the adjusting crank 18 is rotated in one direction or the other, nut 25 travels in one direction or the other along screw 22. 30 A link 26 is secured to an upward extension of nut 25, at 27, and the other or forward end of this link is pivotally connected as shown at 28 to a thin disk 29 which is mounted for rotation on stud 30 extending 35 through plate 14. This rotary disk 29 has an upward extension 31 to which the indicator 17 is secured.

A sector 32 is mounted for rotation on stud 30 immediately on the outer side of 40 plate 14, this sector having a flanged rim portion which is toothed to form a segment of an internal gear as is shown at 33. The sector is also provided with a web portion 34 which is mounted for rotation on stud 45 30 as stated.

The disk 29 carries an outwardly extending pin 35 which extends through a slot 36 in plate 14 and also through slot 37 of the web 34 of sector 32, slots 36 and 37 being 50 curved on arcs concentric with stud 30. Pin 35 carries a pinion 38 which meshes with the teeth 33 of sector 32. A pinion 39 is mounted on pin 35 outwardly from pinion, 38, pinion 39 meshing with a gear 40 mounted on stud 30. A cam disk 41 is concentric with and secured to or integral with gear 40, this cam disk being held in position by a nut 42 at the extreme outer end of stud 30.

From the foregoing it will be clear that 60 rotation of hand crank 18 results in the oscillation of disk 29 in one direction of rotation or the other, and in the consequent rotation of pinion 38 about its axis as it travels in a circular path about the axis of stud 30 65 and is at the same time constrained to rotate

because of being in mesh with the gear teeth 33 of the circular rack 32. Pinion 39 rotates with pinion 38 and turns gear 40 to adjust cam 41 into one angular position or another.

Shaft 43 is constantly rotated during the 70 operation of the machine by a chain of idlers 44, 44 from the shaft 6 of hand crank 2 which is geared to the stud shaft 4 of the rotary drum. A pair of cams 46, 47 are secured to shaft 43 on the outer or front 75 side of plate 14. A bell crank pivoted at 48 on the outer face of the plate 14 is provided with a pair of arms 49 and 50 carrying rollers at their outer ends which engage respectively with cams 46 and 47. The bell crank also has a downwardly extending arm 51 to which a link 52 is pivotally connected at one end, the other end of the link being pivotally connected at 53 to the web 34 of sector 32. Cams 46 and 47 are so designed as to oscillate the bell crank about stud 48 80 once during each two revolutions of hand crank 2, the gearing ratio between shafts 43 and 6 being two to one. As the bell crank oscillates, the circular rack 32 is swung forwardly and back and cam 41 is oscillated 85 in reverse direction to the circular rack through the pinions 38 and 39.

90 The breaker rod or paper weight rod 12 has end portions 12' of reduced diameter 95 mounted in slots 54 of the side arms 55 of the breaker rod frame or paper weight frame 55', arms 55 being pivoted at 56, 56', spring 57 tending to hold the paper weight frame in depressed position. The end portions 12' of rod 12 are pivotally connected to the ends of links 58, 58'. Links 58, 58' are pivotally connected to the ends of levers 59, 59', which are pivoted on the studs 56, 56'. A link 61 is pivotally connected at one 100 end to lever 59, at a point 62 below the pivot pin 56, and at the other end to the disk 29 at 63. The bottom end of lever 59 is connected by a link 64 and arm 65 (Fig. 3) to a rod 66 which extends across the machine and 110 is rotatably supported in the side frame members 67, 67 of the machine. At its opposite end shaft 66 is connected by arm 65' and link 64' to the lever 59' which is pivoted at 56' to the adjacent side frame 67 of the 115 machine. Link 58' pivotally connects the upper end of lever 59' in the adjacent end of paper weight rod 12.

120 It will be obvious that as hand crank 18 is rotated in a clockwise direction, to advance the pointer 17 from the "thin" toward the "thick" end of scale 16, disk 29 being correspondingly oscillated, levers 59 and 59' will be rotated about their pivots in a counterclockwise direction, referring to 125 Figs. 3 and 4, so as to move the rod 12 to the left, that is at a farther distance from the feed rollers 10. Accordingly when the parts have been adjusted in this direction, the rod 12 will press upon the top sheet upon 130

the table 5, at intervals in the operation of the machine, at a greater distance from feed rollers 10. Similarly when hand crank 18 is rotated in counterclockwise direction, the 5 pointer 17 will move toward the "thin" end of scale 16 and levers 59 and 59' will move in the opposite direction, to cause rod 12 to engage the top sheet at a point which is nearer to the feed rollers 10.

10 The table 5 is pivotally supported at the rear on rod 68 in the usual manner. The table 5 has a slotted plate 69 secured to the under side of the same, and a lever 70 secured at one end on shaft 71 has a roller 15 72 at its other or rear end which engages in the slot.

As table 5 is rocked about its pivot 68 shaft 71 will accordingly be rocked, and vice versa, shaft 71 being supported in the 20 opposite side frames 67 of the machine. An arm 72 secured to shaft 71 has a spiral spring 73 extending forwardly from the lower end of the same. The forward end of this spring is secured to a member 74. An arm 75 is secured at its upper end to a pin 76 which is 25 rotatably supported from the inner side of plate 14. The lower end of arm 75 is bifurcated and engages member 74. A lever arm 77 is also secured to pin 76, arm 77 carrying 30 at its lower or forward end a roller 78 which bears against the periphery of a cam plate 79 which is secured to the disk 29.

When hand crank 18 is rotated in direction to advance the pointer 17 in a right 35 handed direction over the scale 16, that is toward the end of the scale marked "Thick", disk 29 and cam 79 are moved through a partial rotation so as to lower roller 78 and accordingly to move arm 75 to the left, referring to Fig. 3, so as to increase the tension 40 on spring 73, with the result of causing table 5 to press the paper sheets upwardly against the feed rollers 10 with an increased pressure. Similarly when crank 45 18 is rotated in the opposite direction, the tension on spring 73 will be decreased so as to decrease the pressure with which table 5 presses the sheets upwardly.

I have now described how the operation 50 of hand crank 18 varies the position of paper weight rod 12 and at the same time the pressure exerted on the top sheet while the same is in contact with the feed rollers 10. As stated above, a third effect is also 55 produced by the rotation of hand crank 18, namely, the variation of the time during which this pressure is exerted on the paper by the table 5 below the same and the feed rollers 10 above the same. This may be accomplished by holding table 5 in its uppermost position for a greater or less length of time in relation to the rotation of drum 1.

This is effected by the position of cam 41.

An arm 80 on the front or outer side of 60 plate 14 is secured at its upper, rearward

end to a shaft 81 which is rotatably mounted in plate 14 at one end and in a plate 82 mounted on the base 83 of the machine beyond the side frame 67 on the opposite side of the machine. Arm 80 carries a roller 84 70 at its lower end which bears against the surface of cam 41. During the operation of the machine cam 41 will be oscillated forward and back as described, to oscillate shaft 81.

Arm 72', which as stated is secured to 75 shaft 71, has a rearwardly extending arm 85 integral therewith or secured thereto, this arm having a ratchet 86 formed at its rear end. A second lever 87 is mounted on shaft 71 to turn freely thereabout, this lever 80 having a tail or extension 88 extending downwardly from shaft 71. This arm 88 is connected by a spiral spring 89 with the rear portion of the base 83, the effect of this spring being to tend to move arm 87 upwardly.

A pin 90 is carried by the rear end of arm 87 and an arm 91 secured on shaft 81 constantly bears on this pin. Since arm 87 is pressed upwardly by spring 89, the action 90 of this spring is to hold roller 84 constantly up against the surface of cam 41.

A pawl carrier 92 is pivotally secured to pin 90 to extend upwardly therefrom. A spring 93 secured to member 92 at one end 95 and to arm 87 at the other constantly tends to swing member 92 in a right handed direction, referring to Fig. 4. A pawl 94 on member 92 is adapted to engage the teeth of ratchet 86, so that when member 92 is depressed the pawl will engage one of the ratchet teeth to swing arm 85 downwardly and accordingly to lower table 5.

Pawl carrier 92 is provided with a roller 95 which is adapted to engage against the 105 lower edge of a bracket 96 which is secured to the adjacent side frame member 67, when member 92 rises, to cam member 95 rearwardly, that is to the left, referring to Fig. 4, to disengage pawl 94 from ratchet 86.

The operation of this feature of the mechanism will now be plain. The adjustment of hand lever 18 positions cam 41 in one position or another relative to roller 84. When hand crank 18 is moved to swing pointer 17 115 to the right, that is toward the "Thick" end of the scale 16, cam 41 is adjusted so that the low portion of its periphery 97 will be in contact with roller 84 for the greater part of the forward and back movement of cam 120 41 and the high part of the cam 98 for a less time. When, however, the pointer 17 is moved to the "Thin" end of scale 16, roller 84 will contact the high part 98 of the cam for the greater part of the movement and 125 will contact against the low part 97 for a comparatively brief period each operation.

When roller 84 rides on to the high part 98 of the cam from the low part, arm 91 is swung downwardly and pawl 94 engages a 130

tooth of ratchet 86 and carries the same down, depressing table 5, which is held in depressed position until roller 84 rides off the high part 98 on to the low part 97 of 5 cam 41. When this happens table 5 rises to its top position, pawl 94 being cammed out of engagement with ratchet 86 by the engagement of roller 95 with the bracket 96. Accordingly the table will be in its upper 10 position, with the pressure of spring 73 pressing the same up, for a longer period each cycle of operations, as hand crank 18 is rotated to progress pointer 17 toward the right in Fig. 3.

15 In the operation of the machine if it is noted that the feed rollers 10 are failing to pick up each top paper sheet in its proper order, it is only necessary to turn crank 18 in a right handed direction until each sheet 20 is properly picked up. If on the other hand, two or more sheets are being picked up at a time, crank 18 is rotated in a left hand direction, to decrease the pressure of spring 73, the time of contact and the distance between rod 12 and the feed rollers, 25 until one sheet only is being properly picked up each operation.

It should be understood that my invention is not limited to the exact details of construction described, but is as broad as is indicated by the accompanying claims.

For the sake of clearness, various details of construction of the stencil-duplicating machine as it existed before my present invention are not shown or described.

What I claim is:—

1. In a duplicating machine, the combination with a table for a pile of sheets, means for buckling the forward end of the top 40 sheet, to separate it from the pile, bearing means to exert pressure on the top sheet, to the rear of the portion buckled, and resilient means to cause said buckling means to exert pressure on the top sheet while it is operating, all of said means coming into operation 45 periodically, of means to adjust the length of time of application of said buckling means, the distance between said bearing means and buckling means, and the amount 50 of pressure exerted by said resilient means, and means for operating all of said adjusting means together.

2. In a duplicating machine, the combination of a table, means to lower and raise and 55 hold the same raised for an interval, repeatedly, during the operation of the machine, a feeding roller above said table, adapted to coact with the top sheet of a pile on said table, when said table is raised, a paper- 60 weight bar, adapted to bear upon the top of the pile at a distance to the rear of said roller, means for adjusting the distance to the rear of said roller at which said bar bears upon the pile, means for adjusting the

time said table remains in its raised position, each operation, and a single manually-operated member for operating both of said adjusting means. 65

3. In a duplicating machine, the combination of a table, means to lower and raise and hold the same raised for an interval, repeatedly, during the operation of the machine, a feeding roller above said table, adapted to coact with the top sheet of a pile on said table, when said table is raised, a paper-weight bar, adapted to bear upon the top of the pile at a distance to the rear of said roller, means for adjusting the distance to the rear of said roller at which said bar bears upon the pile, means for exerting upward 80 pressure on said table when it is raised, means for adjusting the amount of said pressure, and a single manually-operated member for operating both of said adjusting means. 85

4. In a duplicating machine, the combination of a table, means to lower and raise and hold the same raised for an interval, repeatedly, during the operation of the machine, a feeding roller above said table, adapted to coact with the top sheet of a pile on said table, when said table is raised, a paper-weight bar, adapted to bear upon the top of the pile at a distance to the rear of said roller, means for exerting upward pressure 90 on said table when it is raised, means for adjusting the amount of said pressure, means for adjusting the time said table remains in its raised position, each operation, and a single manually-operated member for operating both of said adjusting means. 95

5. In a duplicating machine, the combination of a table, means to lower and raise and hold the same raised for an interval, repeatedly, during the operation of the machine, a feeding roller above said table, adapted to coact with the top sheet of a pile on said table, when said table is raised, a paper-weight bar, adapted to bear upon the top of the pile at a distance to the rear of said roller, means for adjusting the distance to the rear of said roller at which said bar bears upon the pile, means for exerting upward pressure on said table when it is raised, means for adjusting the amount of said pressure, means for adjusting the time said table remains in its raised position, each operation, and a single manually-operated member for operating all three of said adjusting means. 110 115

6. In a duplicating machine, the combination of a table, a feeding roller above the forward end portion of said table, means for moving said table and roller relatively apart, and toward each other, and holding them for an interval in position for said roller to coact with the top sheet of a pile on said table, cyclically, a paper-weight bar, adapted to 125

- bear upon the top of the pile at a distance to the rear of said roller, means for adjusting the time said roller can coact with the top sheet, means for adjusting the distance 5 between said roller and bar when the latter bears on the pile, and a single member for operating both of said adjusting means.
7. In a duplicating machine, the combination of a table, a feeding roller above the forward end portion of said table, means for moving said table and roller relatively, cyclically, into and out of position for said roller to coact with the top sheet of a pile on said table, means for adjusting the time 10 said roller can coact with the top sheet, each cycle, means for adjusting the pressure exerted on the top sheet by said roller, when coacting therewith, and a single member for operating both of said adjusting means.
- 20 8. In a duplicating machine, the combination of a table, a feeding roller above the forward end portion of said table, means for moving said table and roller relatively, cyclically, into and out of position for said roller to coact with the top sheet of a pile on said table, means for adjusting the pressure exerted on the top sheet, each cycle, when said roller contacts the same, a bar adapted to bear on the top sheet to the rear 25 of said roller, when said roller coacts with said sheet, means to adjust the distance between said bar and roller at such times, and a single member for operating both of said adjusting means.
- 30 9. In a duplicating machine, the combination of a table, a feed roller above the same, means to lower and raise said table and hold the same in lowered and raised positions, repeatedly, during the operation of the machine, comprising a cam, having two concentric portions, a roller riding on said cam, and connections between said roller and table for raising or lowering said table as said roller passes from one portion of said cam 35 to the other, or vice versa, means for swinging said cam forward and back, repeatedly, and means for adjusting the angular position of said cam.
- 40 10. In a duplicating machine, the combination of a table, a feed roller above the same, means to lower and raise said table and hold the same in lowered and raised positions, repeatedly, during the operation of the machine, comprising a cam, having two concentric portions, a roller riding on said cam, and connections between said roller and table for raising or lowering said table as said roller passes from one portion of said cam 45 to the other, or vice versa, means for swinging said cam forward and back, repeatedly, and means for adjusting the angular position of said cam.
- 50 11. In a duplicating machine, the combination of a table, a feed roller above the same, means to lower and raise said table and hold the same in lowered and raised positions, repeatedly, during the operation of the machine, a manually-operable member, a pivoted plate; connections for varying the angular position of said plate as said member is operated, and connections between said plate and cam for adjusting the angular position of said cam.
- 55 12. In a duplicating machine, the combination of a table, a feed roller above the same, means to lower and raise said table and hold the same in lowered and raised positions, repeatedly, during the operation of the machine, comprising a cam, having two concentric portions, a roller riding on said cam, and connections between said roller and table for raising or lowering said table as said roller passes from one portion of said cam to the other, or vice versa, an internally toothed sector, means for swinging the same forward and back during the operation of the machine, a pivoted plate, means for adjusting the angular position of the same, a pin on said plate, a pinion rotatable about 60 said pin and meshing with said sector in all positions of said plate, a gear secured to said cam, and a pinion concentric with and secured to said first pinion, meshing with said gear.
- 65 13. In a duplicating machine, the combination of a table, a feed roller above the same, means to lower and raise said table and hold the same in lowered and raised positions, repeatedly, during the operation of the machine, comprising a cam, having two concentric portions, a roller riding on said cam, and pivoted connections between said roller and table for raising and lowering the latter as said roller passes from one portion of said cam to the other, or vice versa, a spring pressing said table upwardly and holding said roller in contact with said cam, means for swinging said cam forward and back repeatedly, a manually controlled member, and means operable therefrom for adjusting the angular position of said cam and the tension of said spring.
- 70 14. In a duplicating machine, the combination of a table, a feed roller above the same, means to lower and raise said table and hold the same in lowered and raised positions, repeatedly, during the operation of the machine, a manually-operable member, a pivoted plate, connections for varying the angular position of said plate as said member is operated, a spring tending to press said table upwardly, and connections from

said plate for varying the tension of said spring in accordance with the angular position of said plate.

15. In a duplicating machine, the combination of a table, a feed roller above the same, means to lower and raise said table and hold the same in lowered and raised positions, repeatedly, during the operation of the machine, a manually-operable member, 10 a pivoted plate, connections for varying the angular position of said plate as said member is operated, a spring tending to press said table upwardly, connections between said plate and said table raising and lowering means for adjusting the timing of the latter, and connections between said plate and spring for varying the tension of the latter, both in accordance with the angular position of said plate.
16. In a duplicating machine, the combination of a table, means to lower and raise and hold the same raised for an interval, repeatedly, during the operation of the machine, a feeding roller above said table, 15 adapted to coact with the top sheet of a pile on said table, when said table is raised, a paper-weight bar, adapted to bear upon the top of the pile at a distance to the rear of said roller, a manually-operable member, 20 a pivoted plate, connections for varying the angular position of said plate as said member is operated, and means governed by the position of said plate for adjusting the distance to the rear of said roller at which said 25 bar bears upon the pile.

17. In a duplicating machine, the combination of a table, means to lower and raise and hold the same raised for an interval, repeatedly, during the operation of the machine, a feeding roller above said table, 30 adapted to coact with the top sheet of a pile on said table, when said table is raised, a paper-weight bar, adapted to bear upon the top of the pile at a distance to the rear of said roller, a manually-operable member, 35 a pivoted plate, connections for varying the angular position of said plate as said member is operated, and means governed by the position of said plate for adjusting the distance to the rear of said roller at which said 40 bar bears upon the pile.

18. In a duplicating machine, the combination of a table, means to lower and raise and hold the same raised for an interval, repeatedly, during the operation of the machine, a feeding roller above said table, 45 adapted to coact with the top sheet of a pile on said table, when said table is raised, a paper-weight bar, adapted to bear upon the top of the pile at a distance to the rear of said roller, a manually-operable member, 50 a pivoted plate, connections for varying the angular position of said plate as said member is operated, and means governed by the position of said plate for adjusting the distance to the rear of said roller at which said 55 bar bears upon the pile, and means governed by the position of said plate for adjusting the time said table remains in its raised position, each operation.
19. In a duplicating machine, the combination of a table, means to lower and raise and hold the same raised for an interval, 60 repeatedly, during the operation of the machine, a feeding roller above said table, adapted to coact with the top sheet of a pile on said table, when said table is raised, a paper-weight bar, adapted to bear upon the top of the pile at a distance to the rear of said roller, a manually-operable member, 65 a pivoted plate, connections for varying the angular position of said plate as said member is operated, a spring for exerting upward pressure on said table when it is raised, and means governed by the position of said plate for adjusting the distance to the rear of said roller at which said bar bears upon the pile, and for adjusting the tension of said spring.

19. In a duplicating machine, the combination of a table, means to lower and raise and hold the same raised for an interval, 70 repeatedly, during the operation of the machine, a feeding roller above said table, adapted to coact with the top sheet of a pile on said table, when said table is raised, a paper-weight bar, adapted to bear upon the top of the pile at a distance to the rear of said roller, a manually-operable member, a pivoted plate, connections for varying the angular position of said plate as said member is operated, a spring for exerting upward pressure on said table when it is raised, means governed by the position of said plate for adjusting the distance to the rear of said roller at which said bar bears upon the pile, and for adjusting the tension of said spring.

19. In a duplicating machine, the combination of a table, means to lower and raise and hold the same raised for an interval, 75 repeatedly, during the operation of the machine, a feeding roller above said table, adapted to coact with the top sheet of a pile on said table, when said table is raised, a paper-weight bar, adapted to bear upon the top of the pile at a distance to the rear of said roller, a manually-operable member, a pivoted plate, connections for varying the angular position of said plate as said member is operated, a spring for exerting upward pressure on said table when it is raised, means governed by the position of said plate for adjusting the distance to the rear of said roller at which said bar bears upon the pile, and for adjusting the tension of said spring, an oscillating cam governing the timing of said table raising and lowering means, and connections between said plate and cam for adjusting the angular position of said cam.

20. In a duplicating machine, the combination with a table for a pile of sheets, means for buckling the forward end of the top sheet, to separate it from the pile, bearing means to exert pressure on the top sheet, to the rear of the portion buckled, and resilient means to cause said buckling means to exert pressure on the top sheet while it is operating, all of said means coming into operation periodically, of means for increasing or decreasing proportionally the length of time of application of said buckling means, the distance between said bearing means and buckling means, and the amount of pressure exerted by said resilient means, and a single manually-operable member for operating said increasing and decreasing means.

21. In a duplicating machine, the combination with a table for a pile of sheets, 115 means for buckling the forward end of the top sheet, to separate it from the pile, bearing means to exert pressure on the top sheet, to the rear of the portion buckled, and resilient means to cause said buckling means 120 to exert pressure on the top sheet while it is operating, all of said means coming into operation periodically, of means for increasing or decreasing proportionally the length of time of application of said buckling means, 125 the distance between said bearing means and buckling means, and the amount of pressure exerted by said resilient means, a scale, a pointer adapted to move over said scale proportionately to the adjustments made, 130

and a manually controlled member for operating said pointer and said increasing and decreasing means.

22. In a duplicating machine, the combination of a table, a feed roller above the same, means to lower and raise said table and hold the same in lowered and raised positions, repeatedly, during the operation of the machine, a manually-operable member, a pivoted plate, connections for varying the angular position of said plate as said member is operated, a scale, a pointer carried by said plate and adapted to move over said scale, and connections between said plate and table raising and lowering means, for adjusting the timing of the latter in accordance with the angular position of said plate.

23. In a duplicating machine, the combination of a table, a feed roller above the same, a frame member, a plate rotatably mounted on said member, a screw, a nut adapted to travel thereon as said screw revolves, a connection from said nut for varying the angular position of said plate, means for raising and lowering said table, repeatedly, during the operation of the machine, means for varying the timing of said raising and lowering means in accordance with the angular position of said plate, and means for rotating said screw.

24. In a duplicating machine, the combination of a table, a feed roller above the same, a frame member, a plate rotatably mounted on said member, a screw, a nut adapted to travel thereon as said screw revolves, a connection from said nut for varying the angular position of said plate, means for raising and lowering said table, repeatedly, during the operation of the machine, a spring for pressing said table upwardly when in its raised position, means for in-

creasing or decreasing the tension of said spring as said plate swings in one direction or the other, and means for rotating 45 said screw.

25. In a duplicating machine, the combination of a table, a feed roller above the same, a frame member, a plate rotatably mounted on said member, a screw, a nut 50 adapted to travel thereon as said screw revolves, a connection from said nut for varying the angular position of said plate, means for raising and lowering said table, repeatedly, during the operation of the machine, a 55 paper-weight bar adapted to bear upon a pile of sheets on said table at a distance to the rear of said roller, a connection between said plate and bar for adjusting the distance between said bar and roller, and 60 means for rotating said screw.

26. In a duplicating machine, the combination of a table, a feed roller above the same, a frame member, a plate rotatably mounted on said member, a screw, a nut 65 adapted to travel thereon as said screw revolves, a connection from said nut for varying the angular position of said plate, means for raising and lowering said table, repeatedly, during the operation of the machine, 70 a spring for pressing said table upwardly when in its raised position, a cam on said plate, a roller bearing on said cam, lever connections between said roller and spring 75 for adjusting the tension of said spring as said plate swings in one direction or the other, and means for rotating said screw.

This specification signed and witnessed this 9th day of June, 1920.
